UNITED STATES PATENT OFFICE.

EUREKA C. BOWNE, OF TRENTON, NEW JERSEY.

NON-REFILLABLE BOTTLE.

SPECIFICATION forming part of Letters Patent No. 606,507, dated June 28, 1898.

Application filed October 20, 1897. Serial No. 655,798. (No model.)

To all whom it may concern:

Be it known that I, EUREKA C. BOWNE, a citizen of the United States, residing at Trenton, in the county of Mercer and State of New Jersey, have invented certain new and useful Improvements in Non-Refillable Bottles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is primarily to prevent a bottle, and more particularly a glass bottle, from being filled and used a second time after having been once filled and used, to reduce the cost of construction of 20 such a bottle, to facilitate the work of removing or severing the top or open extremity of the bottle, to secure a more perfect severance or removal of said extremity, so that the bottle may be employed for purposes other than 25 for which it is first used, and to secure other advantages and results, some of which may be referred to hereinafter in connection with the description of the working parts.

The invention consists in the improved non-refillable bottle, in the cutting device for removing the top or open upper end of said bottle, and in the arrangements and combinations of parts of the same, all substantially 30 as will be hereinafter set forth, and finally 35 embraced in the clauses of the claim.

Referring to the accompanying drawings, in which like letters of reference indicate corresponding parts in each of the views, Figure 1 is a central vertical section taken through 40 the neck or upper end of the bottle and the device contained therein; and Fig. 2 is a horizontal section taken at line α , Fig. 1.

In said drawings, H indicates the neck or upper end of the bottle, which is made, preferably, of cylindrical shape and of considerable length, so as to permit of the bottle retaining a contracted mouth or neck of sufficient length for the usual bottle purposes after the removal of the upper portion thereof.

45 At the top or upper extremity of the bottle is fitted a metallic cap or upper bearing-plate G, which is centrally perforated, as indicated

55 at g, and in this central perforation is arranged a tubular shank J, at the upper end of which, above the plate G, is arranged or furnished a finger-piece I, which may be integral with 60 said tubular shank or may be applied thereto as an independent part. Said finger-piece I is vertically bored at its center, and the opening, which is in axial center line with the chamber of the tubular shank, is provided with a female thread. At the lower extremity of the said tubular shank J, within the neck of the bottle, the said shank is provided with a pair of cutting-arms M M, projecting 65 from opposite sides of the shank J in the same vertical plane, and at a point considerably higher up a pair of guiding-arms K K project from opposite sides of the shank, but in a 70 plane at right angles to the plane of the said cutting-arms M M. These cutting-arms and guiding-arms are preferably arranged oppositely in their relations to the shank J, as indicated in Fig. 2, the guiding-arms K K being turned upwardly through a limited angle 75 and the cutting-arms M M being turned or extended downwardly, forming at the lower end of the tubular shank a V-shaped aperture. All said arms are preferably longitudinally 80 tapering, being made thickest at the base and small at the outward extremities to secure the necessary rigidity and strength requisite when the device is turned, as hereinafter described.

85 While I have shown two guiding-arms and two cutting-arms, I do not wish to be limited to that number, it being evident that a greater number might be used without departing from the spirit or scope of the invention.

A horizontal groove L is formed on the interior of the vertical walls of the neck of the bottle, and the said guiding-arms K K are arranged at such a point on the shank J that the extremities of said arms enter the said groove. This groove serves as a guideway 90 for the arms K, whereby the cutting-arms are caused to travel over a regular course within the bottle-neck in a horizontal plane, so that when the cut is given and the upper part of the bottle severed from the body 95 thereof, as will be hereinafter described, the fracture will be smooth and regular and in a plane at right angles to the central vertical axis of the bottle. The groove also serves 100

to prevent the removal of the severing device, the upward bend or turn in the arms K co-operating with the said groove to prevent withdrawal, as will be understood, it being seen that the said arms K will permit a slight flexion when the device is forced inward, but will resist removal, should the withdrawal be attempted.

At the extremities of the cutting-arms M M are formed knives, which may be sharp points integral with the arms and given cutting capacity by being hardened, or the points may be applied parts of steel, diamond, or other material capable of serving the purpose. Both the cutting-arms M M and the guiding-arms K K may be cast upon the shank J, integral therewith, or may be soldered or otherwise attached thereto in any suitable manner.

Extending longitudinally through the chamber in the shank J is arranged the shank C of a spreader A, said shank being provided at its upper extremity with a thumb-piece A'. Beneath the said thumb-piece A' the said shank C is provided with screw-threads B, adapted to enter the female screw-thread of the centrally-bored finger-piece I, before referred to. The shank C extends down through the hollow tubular shank J, and at its lower extremity is provided with a conical foot or spreader D, the inclined sides of which form a greater acute angle with the longitudinal axis of the bottle than the angle formed with said axis by the under surface of the cutting-arms.

The said foot D engages the outward extremities of the arms M, and when the spreading-foot is elevated by turning the male screw-thread within the female screw-thread in its relation to the part I the arms M are forced into contact with the side walls of the neck of the bottle, said arms being constructed to permit a slight flexion for this purpose.

The spreader under some conditions may be provided with a spiral wire E, which projects downward from the under surface thereof at its center, which spiral wire may serve as a corkscrew for the removal of the plug or cork F, arranged within the neck of the bottle beneath the severing device; but this said corkscrew may be dispensed with without departing from the essentials of this device.

Beneath the severing device the neck of the bottle is provided with the plug or cork F, which serves to retain the liquid within the bottle, but access to this cork can be obtained only after the severing of the upper part of the bottle and the removal of the severing device.

In operating the device, the parts being arranged substantially as described, I simply raise the spreader D by turning the thumb-piece A' and force the spreading-foot into engagement with the under side of the arms M, causing the cutting extremities of the latter to enter into contact with the glass. The thumb-piece I is then turned and the cutting-points, which describe a circle within the

bottle-neck, scratch or cut the glass of the neck, so that the upper portion can be readily severed in a manner common in glass-cutting. 70

Having thus described the invention, what I claim as new is—

1. The combination with a bottle, of a glass-cutter arranged within the neck thereof, and adapted to be turned therein to cut said bottle 75 and render the same capable of being severed, substantially as set forth.

2. The combination with a bottle, and its plug, F, of a plate providing bearings for the severing device, and a severing device, adapted to be turned within the neck of the bottle to scratch or cut the inner walls thereof, substantially as set forth. 80

3. The combination with the bottle having the impermeable plug F, and a bearing-plate 85 G, of a severing device, comprising cutting-arms adapted to be turned in said plate and a spreader adapted to be brought into spreading engagement with said cutting-arms to force the cutting-points into forcible engagement with the side walls of the bottle, substantially as set forth. 90

4. A severing device for bottles, comprising a plate G, adapted to provide bearings for the cutter, a cutter arranged and adapted 95 to be turned in said plate, said cutter having arms provided with cutting-points and a spreader adapted to engage said arms to press the extremities of the same against the side walls of the bottle, substantially as set forth. 100

5. The combination of the hollow shank J, having a finger-piece I, and arms M, extending downwardly, and a spreader comprising a shank C, finger-piece A', and a foot D, said foot being arranged beneath said arms M, and 105 being adapted to be raised into contact with the arms M, to force the same against the sides of the bottle, substantially as set forth.

6. The severing device herein described, comprising the tubular shank J, the finger-piece I, having a threaded central opening, arms M, M, forming a V-shaped aperture at the lower end of the device, and a spreader comprising a shank C, having threads to engage those of the finger-piece I, a finger-piece 115 A', and a foot D, substantially as set forth. 110

7. The combination with the bottle having a groove formed horizontally in the inner walls thereof, of a plate G, provided at its center with a perforation g, in which the severing device has its bearings, a hollow shank, J, having a finger-piece I, arms K, arranged in said groove, arms M, provided with cutting-points, and a spreader comprising the finger-piece A', shank C, and foot D, all arranged and operating, substantially as set forth. 120

In testimony that I claim the foregoing I have hereunto set my hand this 9th day of October, 1897.

EUREKA C. BOWNE.
